DESIGN FOR A LIQUID BEATER

Junius O. Hutton, Chevy Chase, Md.

Application December 12, 1946, Serial No. 135,434

Term of patent 7 years

(Cl. D44—1)

To all whom it may concern:

Be it known that I, Junius O. Hutton, a citizen of the United States, residing at Chevy Chase, in the county of Montgomery and State of Maryland, have invented a new, original, and ornamental Design for Liquid Beaters, of which the following is a specification, reference being had to the accompanying drawing, forming part thereof.

Fig. 1 is a front view of a liquid beater, showing my new design.

Fig. 2 is a side view thereof; and

Fig. 3 is a cross section through the blades taken on line 3—3 of Fig. 1.

I claim:

The ornamental design for a liquid beater, as shown.

J. O. HUTTON.
